[57] CLAIM

The ornamental design for a train case, as shown.

DESCRIPTION

FIG. 1 is a perspective view of a train case showing our new design;

FIG. 2 is a right side elevational view;

FIG. 3 is a top plan view;

FIG. 4 is a rear elevational view.

The bottom of the train case is plain and unornamented except for the end stitching and the rivet-like support members.

FIG. 3.

FIG. 4.
